UNITED STATES PATENT OFFICE.

EDMUND C. MORGAN, OF MORGAN PARK, ILLINOIS.

MINING MACHINE.

1,424,113.

Specification of Letters Patent. Patented July 25, 1922.

Application filed June 27, 1910, Serial No. 569,173. Renewed May 18, 1916. Serial No. 98,438.

To all whom it may concern:

Be it known that I, EDMUND C. MORGAN, a citizen of the United States, residing at Morgan Park, county of Cook, and State 5 of Illinois, have invented certain new and useful Improvements in Mining Machines, of which the following is a specification.

This invention relates to mining machinery and has for its primary object to 10 provide an improved construction, combination and arrangement of parts in a mining machine.

One of the objects of the present invention is to provide an improved mining machine 15 constructed in sections.

Another object of my invention is the provision of means for producing transverse kerfs in a mine wall while an under kerf is being cut, and intermittently moving cross-cutting mechanism to new positions while the undercutting mechanism continues in 20 operation.

Another object of the invention is to provide cross-cutting mechanism above an undercut in a mine wall and combining therewith dislodging and loading apparatus.

A further object of the invention is to provide in a machine adapted to move substantially parallel to a coal face, the combination of an undercutting means and a 30 breaking down device adapted to attack the coal wall located behind the undercutting means and in a plane transverse and substantially perpendicular to the main face 35 of the coal.

Other and further objects will appear in the specification and be more specifically pointed out in the appended claims, reference being had to the accompanying drawings which exemplify the invention and in 40 which—

Figure 1 is a plan view of the front end of a mining machine constructed in accordance with the principles of this invention.

Figure 1^a is a plan view of the rear end of the same machine.

Figure 2 is a side elevation of the front end of the same machine.

Figure 2^a is a side elevation of the rear 50 end of the same machine.

Figure 3 is a front elevation of the same machine.

Figure 4 is a rear elevation of the machine.

Figure 5 is a section on the line V—V 55 Fig. 1^a.

Figure 6 is a section on the line VI—VI Fig. 1^a.

Figure 7 is a fragmentary sectional view taken on the line 7—7 of Fig. 1^a looking in 60 the direction of the arrows, a portion of the bracket and of the circular movable pin, and the vertical shaft, being shown in elevation.

Referring more particularly to the drawings, the frame work of the machine comprises a forward slidable base member 1 and a rear slidable base member 2, said base members being adjustably connected together preferably by a slide and guide connection shown on the drawings as a bar 3 mounted within a rearwardly extending portion 4 of the forward base member 1. For this purpose the slidable member 2 is provided with laterally projecting arms 5 upon 70 the outer ends of which are the collars or sleeves 6 which slidably engage the bar 3. Upon the front end of the forward member 1, is mounted a winding drum 7 provided with a flexible connection 8 leading 80 to a strut or post 9, which, as shown in Figs. 2 and 3, is imbedded at either end in the upper and lower walls of the gallery. Said strut is provided with an adjustable portion 10 which may be rotated by a wrench 85 or lever 11 so as to secure it firmly in position or to release it from engagement with the roof. The drum 7 is keyed to a shaft 12 upon which is loosely mounted a spiral gear 13 meshing with a spiral worm 14 secured to the end of a drive shaft 15 which receives its motion from a motor 16. The gear 13 has rigidly mounted thereon, a clutch element 17 with which co-operates a clutch element 18 splined on the shaft 12. The 90 clutch element 18 is provided with a grooved collar 19 in which engages a forked lever 20 integrally formed with an operating lever 21 provided with a pawl latch 22 engaging the segment ratchet 23. By this means the spiral gear 13 may, whenever desired, be locked to the shaft 12 so that should the motor 16 be running, the drum 7 would be rotated to wind the cable 8 thereon and thus cause the entire machine 100 to slide over the floor of the mine, or should occasion demand it, the base member 1 can be moved forward with the undercutting tool presently to be described, while the rear section of the machine remains 105 stationary. The drive shaft 15 has keyed thereto a spiral worm 24 which meshes

with a worm gear 25 for driving the undercutting tool head 26. A gear 27 on the end of the drive shaft 15 transmits power to a gear 28 keyed to an intermediate shaft 29, said shaft 29 being extended rearwardly and provided by means of a universal coupling 30 with a flexible connection to an extensible shaft 31, the other end of said extensible shaft 31 being connected by a universal joint 32 with a short driven shaft 33.

Referring now more especially to Figures 1^a and 2^a, the shaft 29 is connected by bevel gears 34 and 35 through the intermediate of an extensible shaft 36, with a cutter shaft 37 upon which is carried a rotary cross-cutting tool 38. The cross-cutting tool 38, together with the shaft 37, is journaled within a carriage 39, mounted upon the forward member of the base and which carriage may be traversed toward the coal by means of a rack 40 rigidly mounted on said carriage 39. A second rack 41, also rigidly mounted on the carriage 39, serves for the return movement of the carriage. To effect these movements, a vertical spindle 42 Fig. 5 has keyed thereto a worm gear 43 with which inter-meshes a worm 44 keyed to the shaft 37. Upon the lower end of the spindle 42 is loosely journaled a small pinion 45 provided with a clutch element 46. A larger spur gear 47 is loosely journaled upon the spindle 42 above the pinion 45, while between said pinion and gear is a clutch element 48 slidably mounted on the spindle 42 but held against turning thereon by means of a spline 49. A shifting lever 50 operably engaging the clutching element 48 serves to shift said clutch element into clutch with either of the gears 45 or 47, the pinion 45 being adapted to impart the slow inward movement to the carriage 39 while the larger gear 47 serves to impart the quick return thereto. The carriage 39 is reciprocally mounted in guides or ways 51 which overhang the shaft 29.

In order to bring down the coal which has been channeled by an undercut and grooved by a cross-cut, a picking device (Fig. 1^a) is mounted upon the rear base member 2 and preferably comprises a picking tool 52 reciprocally mounted within a housing 53 by means of a plunger 54 having a piston 55 which is adapted to be acted upon by any suitable elastic fluid in the well known manner not specifically concerned in the present invention. The housing 53 is provided with trunnions 54¹ rotatably mounted under the arms of a bearing fork 55¹. Said bearing fork 55¹ is in turn pivotally mounted upon an upright or standard 56 (Fig. 2^a) to oscillate about a vertical axis. The pick 52 is thus mounted to have a universal movement and the housing 53 is provided with a handle 57 whereby the direction of the picking action 65 may be controlled. After the coal has been

brought down by the pick 52, gathering mechanism comprising a finger composed of a horizontal plate 58 and a vertical flange or plate 59 along a portion of one edge of the horizontal plate is adapted to displace the coal laterally by being slidably mounted in a bearing block 60 which is pivotally mounted at 61 in the outer end of an arm 62 rigidly connected to the rear member 2. A pin 63 projecting from the blade of the finger 58 75 pivotally engages a rotary disk 64 keyed to a spindle 65 (see Fig. 4) upon which is also keyed a beveled gear 66. A pinion 67 (Fig. 1^a) meshing with the gear 66 transmits power thereto by means of an extensible 80 shaft 68 which receives its power through a pinion 69 from the beveled gear 70 which in turn meshes with a gear 71 keyed to the driven shaft 33, hereinbefore referred to. The beveled gear 70 is keyed to 85 a stub shaft 72 upon which is also keyed a sprocket wheel 73 for driving an endless chain 74, said endless chain being provided with outwardly projecting arms or flights 75 into the path of movement of which the coal is moved by means of the finger 58. The flight conveyer, comprising the endless chain 74 and the projecting flights or arms 75, is operatively mounted within a chute 76 projecting upwardly and rearwardly from 90 the base member 2. A lateral rail or flange 77 of the chute 76, serves to confine the coal to the chute. In order to adapt the chute to be readily adjusted in position on the base member 2, said chute is provided adjacent its 100 lower end (see Fig. 6) with a ball and socket joint 78 and with a vertically adjustable abutment or support 79 having a threaded connection with a screw 80 upon which it may be raised or lowered by means of a hand wheel 81. A pedestal 82 is connected by a link 83 with a loop 84 secured to said chute in such manner as to anchor said chute to limit its movement. The inner lower end of said chute is provided with a projecting 110 scoop portion 85 which is sharpened on its lateral edge to adapt it to be inserted under the coal which is to be removed thereover. The projecting scoop portion 85 is shown in Figs. 4 and 6 as constituting a plate adapted 115 to occupy a position at the receiving end of the conveyer in the plane of the under kerf. In order to adjust the position of the base member 2 relatively to the base member 1 and thus adjust the cross-cutting tool 38 120 relatively to the undercutting kerf cutter 26, a cable 86 (see Fig. 1^a) is secured to an eye 87 rigidly mounted upon a web 88 on the rearwardly extending portion of the forward member 1. The cable 86 may be wound upon 125 a drum 89 (see Figs. 1^a and 4) by causing said drum to be rotated on a vertical spindle 90 to which is keyed a beveled gear 91 meshing with a pinion 92 on the end of a shaft 93, the other end of the shaft 93 being pro- 130

vided with a second beveled pinion 94 which meshes with the beveled gear 66, hereinbefore referred to. A shifting lever 95 (Fig. 4) serves to shift a clutch element 96 which is keyed to the spindle 90, into clutching engagement with a clutching surface formed in the drum 89.

The forward base member 1 may, if desired, be provided with a vertically projecting flange 97 so as to maintain the machine accurately in position during the cutting operations, by means of a series of posts 98 vertically disposed at one side of the machine. The flange 97 may engage the posts 98 to guide the mining and loading machine laterally along a coal face and parallel thereto.

With this improved construction, it will be apparent that the rotary undercutting kerf-cutter 26, as shown in Fig. 1, may be continuously advanced along a mine wall during the operation of said kerf-cutter. In order to permit the cross-cutting rotary kerf-cutter 38, as shown in Fig. 1^a, to operate during the feeding movement of the undercutter along the mine wall, and in order to permit the cross-cutting tool to be intermittently advanced during the operation of the undercutting tool, the supporting framework of the entire machine is constructed in sections adjustable with respect to each other, the rear sectional frame 2 being slidably mounted on the forward sectional frame 1, as shown in Fig. 1^a; the cross-cutting kerf-cutter has a feeding movement substantially at right angles to the normal upright face of the coal wall, and during the operation of this cross-cutting kerf-cutter the forward sectional frame 1 slides in the brackets 5 of the rear sectional frame. When the cross-cutter is to be advanced forwardly to a new position, a pull is exerted on the rope 86 by means of the mechanism shown in Fig. 1^a to slide the rear sectional frame 2 forwardly on the forward sectional frame.

I have described and claimed in a co-pending divisional application, Serial No. 76,910, filed February 8, 1916, for an improvement in loading apparatus, the specific construction herein disclosed for gathering the broken down coal by moving it into the path of the flight conveyer. This gathering mechanism described and claimed in said co-pending application Serial No. 76,910, comprises the finger 58 having the upright blade 59 and parts connected thereto for operating the same to effect movement of the dislodged coal onto the receiving end of the flight conveyer.

In my co-pending application, Serial No. 210,796, filed January 7, 1918, as a renewal of Serial No. 569,168, originally filed June 27, 1910, for an improvement in mining machines, I have described and claimed a mining and loading machine comprising mecha-

nism for cutting kerfs in a mine wall in intersecting planes, a pick machine, a conveyer, and gathering mechanism for moving material dislodged by the pick machine onto the conveyer, but in that combination a core 70 of material is cut in the mine wall by the kerf-cutting mechanism, while in the present application the plane of the vertical kerf-cutter intersects the plane of the undercutter without cutting such a core and, furthermore, in Serial No. 210,796 the pick machine acts substantially at right angles to the normal upright face of the coal wall, whereas, in the present application the pick machine is adapted to operate on an advancing coal face in vertical planes substantially at right angles to the normal coal face parallel to which the mining machine is moved during the feed of the undercutter. I therefore wish to claim more broadly in 85 the present application such combinations with the intersecting kerf-cutting mechanism as are common to the two applications, retaining in Serial No. 210,796, claims directed to subject-matter disclosed therein 90 and not disclosed in the present application, while the claims in Serial No. 76,910 are directed to the gathering mechanism per se and the combination of the gathering mechanism and dislodging mechanism. 95

What I claim is:

1. In a mining machine, the combination with a supporting frame, of cutting mechanism mounted thereon and movable bodily therewith into positions to cut horizontal kerfs, an additional supporting frame connected to said first-named supporting frame in fixed relation thereto but movable relatively thereto, cutting mechanism mounted on said additional frame and movable bodily therewith into positions to cut upright kerfs transverse to the coal face, and means for operating said cutting mechanisms. 100

2. In a mining machine, the combination with a supporting frame, of cutting mechanism mounted on said supporting frame in position to cut a horizontal kerf, an additional supporting frame permanently mounted on said first named frame for movement relatively thereto and in fixed relation to said first named frame, cutting mechanism mounted on said additional frame and movable bodily therewith into positions to cut transversely of the coal face, and means for operating both of said cutting mechanisms from a single source of power during the various positions of said additional frame relatively to said first named frame. 115

3. In a mining machine, the combination with supporting framework comprising relatively slidable sections, a kerf cutter mounted on one section and movable bodily therewith in position to cut a substantially horizontal kerf in an upright mine wall, an ad- 125

- ditional kerf cutter mounted on the other section in position to cut an upright kerf in said upright mine wall, means for driving said kerf cutters, and separate means for 5 feeding said kerf cutters.
4. In a mining machine, the combination with a frame, of kerf cutting mechanism mounted thereon, means for operating said kerf cutting mechanism including the feed 10 thereof by movement of said frame, a reciprocable coal-breaking device, means for supporting said coal-breaking device on said frame for movement relatively thereto, and means for operating said device during 15 the operation of said cutting mechanism including the feed of the latter.
5. In a coal mining machine, the combination of a forward base member having a rotary cutter operating in a horizontal plane 20 adjacent the floor of a mine, a rear base member movable toward and away from the forward base member and having a vertically disposed rotary cutter operating in a plane transverse to that in which the other 25 cutter operates, a motor mounted on one of the base members, and means for operatively connecting each cutter to said motor.
6. In a coal mining machine, the combination of a forward base member having a 30 rotary cutter operating in a horizontal plane adjacent the floor of a mine, a rear base member movable toward and away from the forward base member and having a vertically disposed rotary cutter operating 35 in a plane transverse to that in which the other cutter operates, a motor mounted on one of the base members, means for operatively connecting each cutter to said motor, and means mounted on the forward base 40 member and operably connected to said motor for drawing the machine on the floor of the mine.
7. In a coal mining machine, the combination of a forward base member having a 45 rotary cutter operating in a horizontal plane adjacent the floor of a mine, a rear base member movable toward and away from the forward base member and having a vertically disposed rotary cutter operating 50 in a plane transverse to that in which the other cutter operates, a motor mounted on one of the base members, means for operatively connecting each cutter to said motor, a winding drum mounted on the forward base member, and a releasable clutching mechanism geared to said motor and winding drum.
8. In a mining machine, the combination with a main frame, of a kerf cutter mounted 60 on said main frame in position to cut a horizontal kerf in an upright mine wall, a supplemental frame movable on said main frame, an additional kerf cutter mounted on said supplemental frame in position to cut 65 a kerf in said upright mine wall above the plane of the horizontal kerf, means for moving the main frame to effect the feed of said first named kerf cutter, means for feeding said additional kerf cutter transversely of the upright mine wall, and mechanism 70 for simultaneously driving both of said kerf cutters during the respective feeds thereof and while said main frame moves along said upright mine wall relatively to said supplemental frame. 75
9. In a mining machine, the combination with a main frame, of a kerf cutter mounted on said main frame for operation in approximately a horizontal plane, a supplemental frame carried by said main frame, an additional kerf cutter mounted on said supplemental frame for operation in a substantially vertical plane, means for feeding the said vertical cutter transversely of said supplemental frame, and means for feeding the 80 main frame forward longitudinally together with the horizontal cutter mounted thereon while said supplemental frame is being held substantially stationary while the vertical cutter operates on the mine wall. 85
10. In a mining machine, the combination with a main frame, of a horizontal kerf cutter mounted thereon, a supplemental frame movably mounted on said main frame, a vertical kerf cutter mounted on said supplemental frame, means for feeding said vertical kerf cutter transversely of said supplemental frame, mechanism for feeding forward the main frame together with the horizontal kerf cutter mounted thereon, and apparatus for moving the supplemental frame relatively to the main frame to adjust the 90 position of the vertical kerf cutter. 95
11. In a long wall mining machine, the combination with a main frame, of an under- 100 cutter mounted on said main frame, means for feeding said main frame together with the under cutter thereon along the mine wall while said under cutter is in operation, a supplementary frame slidably mounted on 105 said main frame, a vertical cross cutter mounted on said supplemental frame, means for feeding said cross cutter transversely of said supplemental frame and at substantially right angles to the mine wall during the 110 operation of said cross-cutter, means for simultaneously operating said under cutter, and mechanism operable at will to shift said supplemental frame longitudinally relatively to said main frame to adjust the cross cutter 115 to a new forward position for operation against the mine wall. 120
12. In a mining machine, the combination with a main frame, of a cutter mounted on said main frame and operating in a substantially horizontal plane, means for feeding said main frame forward while said cutter is in operation, a supplemental frame movably mounted on said main frame, an additional cutter mounted on said supplemental frame. 125

mental frame for operation in a substantially vertical plane, means for feeding said vertical cutter transversely of said supplemental frame while said vertical cutter is 5 in operation, apparatus for simultaneously operating both the horizontal cutter and the vertical cutter, means for varying the position of the supplemental frame on said main frame to adjust the position of said vertical 10 cutter, and means for breaking down the material adjacent the cuts produced by said horizontal and vertical cutters.

13. In a mining machine, the combination with supporting framework, of a kerf cutter mounted on said framework in position to cut a kerf along a mine wall in a plane substantially perpendicular thereto, an additional kerf cutter mounted on said framework in position to cut a kerf substantially 20 at right angles to the mine wall but intersecting the kerf cut by said first-named kerf cutter so as to cut a body of material adjacent said framework in intersecting planes, means for adjusting the position of said 25 transverse kerf cutter on said framework relatively to the other kerf cutter, and a universally mounted pick machine mounted on said framework in position to dislodge the said body of material bounded by the 30 intersecting kerfs produced by said kerf cutters.

14. In a mining machine, the combination with a cutter rotatable in one plane, of a second cutter rotatable in a plane trans- 35 verse thereto, means for feeding each of said cutters into an upright mine wall to cut in planes extending transversely of such upright mine wall and each in the plane of its rotation, and means for adjusting one 40 of said cutters relatively to the other in a direction intersecting the plane of action of said adjustable cutter.

15. In a mining machine, the combination with a cutter rotatable in one plane, of a second cutter rotatable in a plane trans- 45 verse thereto, means for feeding each of said cutters into an upright mine wall to cut in planes extending transversely of such upright mine wall and each in the plane of its rotation, means for adjusting one of said 50 cutters relatively to the other in a direction intersecting the plane of action of said adjustable cutter, means for driving one of said cutters, and means for operably connecting the other cutter with the driving mechanism for the first cutter.

16. In a mining machine, the combination with a cutter rotatable in one plane, of a second cutter rotatable in a plane trans- 60 verse thereto, means for feeding each of said cutters into an upright mine wall to operate in planes transversely of such upright mine wall and each in the plane of its rotation, means for adjusting one of said cutters relatively to the other in a direction in-

tersecting the plane of action of said adjustable cutter, means for driving one of said cutters, and means for operably connecting the other cutter with the driving mechanism for the first cutter, said connecting means being flexible and extensible. 70

17. In a mining machine, the combination with supporting framework, of a kerf cutter mounted thereon in position to undercut 75 a wall of coal in an approximately horizontal plane, a second cutter mounted on said framework in position to cut a kerf in a plane transverse to the plane of said first-named kerf cutter, said transverse kerf cutter 80 being initially out of engagement with the coal wall, means for driving both of said kerf cutters from the same source of power, means for simultaneously feeding both of said kerf cutters, and means individual to the said kerf cutters for controlling their feeding movements.

18. In a mining machine, the combination with supporting framework, of a kerf cutter mounted on said framework in position to 90 undercut a wall of coal in an approximately horizontal plane, a second kerf cutter mounted on said framework in position to be initially out of engagement with the coal wall but capable of cutting a kerf in the 95 mine wall in a plane transversely of the plane of the first-named kerf, means for driving both of said kerf cutters from the same source of power, means for feeding the undercutting kerf cutter, means for feeding 100 the second-named kerf cutter into the mine wall transversely of the plane of the kerf produced by the first-named kerf cutter, means individual to said kerf cutters for controlling the feeding movements thereof, 105 and mechanism coacting with the feeding mechanism of the second-named kerf cutter for effecting a quick return of the latter to initial position after such transverse kerf has been cut thereby. 110

19. In a mining machine, the combination with supporting framework, of a cutter mounted on said framework in position to undercut a body of coal, a second cutter mounted on said framework in position to 115 cut such a body of coal transversely of the plane of the said undercut, said second cutter being initially out of engagement with the coal, means for operating said cutters including the feed of each, and means mounted on said framework for moving the second cutter bodily along the mine wall to new positions relatively to the first cutter and at intervals. 120

20. In a mining machine, the combination with an undercutting tool operating adjacent the floor of the mine, of a second cutter operable transversely to the first said cutter, means for driving said cutters, a feeding mechanism for the second cutter, 125 130

means for effecting the operation of the feeding mechanism intermittently, a pick for bringing down the coal cut by said cutters, and framework for supporting said 5 pick in fixed relation with said second cutter.

21. In a mining machine, the combination with an undercutting tool operating adjacent the floor of the mine, of a second 10 cutter operable transversely to the first said cutter, means for driving said cutters, a feeding mechanism for the second cutter, means for effecting the operation of the feeding mechanism intermittently, a pick 15 for bringing down the coal cut by said cutters, a support for said pick, a universal connection between the pick and its support, and framework for supporting said cutters and said pick in fixed relation to each other.

22. In a mining machine, the combination with a supporting frame, of kerf cutting mechanism mounted thereon and movable bodily therewith, a supplemental frame connected to said main frame and movable 25 bodily therewith, said supplemental frame being guided on said main frame for a predetermined limited movement relatively to said main frame and in fixed relation to the latter, additional kerf cutting mechanism 30 mounted on said supplemental frame and movable bodily therewith, said kerf cutting mechanisms being mounted for operation in intersecting planes, means for driving said cutting mechanisms, means for moving said 35 main frame to effect feeding of said first named cutting mechanism, means for feeding said additional cutting mechanism relatively to both of said frames, means for moving said supplemental frame relatively 40 to said main frame to adjust the position of said additional cutting mechanism, and means mounted on said supplemental frame and movable bodily therewith, said breaking down means being in position to dislodge 45 the material cut by said cutting mechanisms.

23. In a machine of the character described, the combination with a forward base member having an undercutting tool mounted thereon and means for feeding said 50 member along a wall of coal, of a rear base member, a transverse cutter mounted on the rear member, means for feeding the last cutter into and out of the coal wall, a motor operably connected with each of said cutters, feeding mechanism, and means for imparting relative movement to said base members.

24. In a mining machine, the combination with a forward base member, of a motor 60 mounted thereon, an undercutting tool driven by said motor, a rear base member slidably connected with said forward base member, a driven shaft carried by the rear base member and operatively connected with said 65 motor, a cross-cutting tool mounted on the

rear base member and operatively connected to said motor, and a winding drum mounted on the rear base member and operatively connected to said driven shaft said winding drum being provided with a flexible connection secured to the forward base member. 70

25. In a coal mining machine, the combination with supporting framework comprising base sections movable relatively to each other but having a fixed relative relation with the relative movement limited, a cutting tool mounted on one of said base sections, and movable bodily therewith to cut a horizontal kerf in an upright mine wall, an additional cutting tool mounted on 80 the other section and movable bodily therewith to positions for cutting upright kerfs in such mine wall, and means mounted on said framework common to both of said cutting tools for operating them simultaneously, including the feed thereof. 85

26. In a coal mining machine, the combination with supporting framework, comprising base sections having limited relative movement and permanently connected 90 together in fixed relation, a cutting tool mounted on one section and movable bodily therewith, another cutting tool mounted on the other section and movable bodily therewith, means common to the cutting tools for 95 operating them simultaneously in the various relative positions of said sections to cut kerfs in an upright mine wall, and means individual to the cutting tool on one section for controlling the feed thereof independently of the feed of the cutting tool on the other section. 100

27. In a mining machine, the combination with an under-cutting kerf cutter, of a second cutter disposed in a plane transverse to the plane of said under-cutting kerf cutter, means for feeding said under-cutting kerf cutter along a mine wall, means for feeding said second kerf cutter into the mine wall while the said under-cutting kerf 110 cutter is operating to produce an under cut, and means for advancing said kerf cutter to a new position during the operation of said under cutter.

28. In a mining machine, the combination with framework, of two cutters mounted thereon in predetermined spaced relation, means for operating said cutters, means individual to said cutters for controlling the feeding movements thereof, and means on 120 said framework for breaking down the material bounded by the cuts made by said cutters.

29. In a mining machine, the combination with a kerf cutter for making an under cut 125 along a mine wall, of a second kerf cutter for making a cut in the mine wall substantially at right angles to the face thereof, means for feeding the under cutter along the mine wall, means for simultaneously 130

feeding the second kerf cutter into the mine wall, and mechanism for effecting intermittent advancement of the second cutter along the mine wall to new positions.

5 30. In a mining machine, the combination with supporting framework comprising two sections having limited relative movement and connected together in fixed relation, of an undercutting kerf cutter mounted on the 10 forward section, means for operating said kerf cutter, a second kerf cutter mounted on the other section of said framework for producing a kerf in the mine wall in a plane substantially at right angles to the 15 plane of said undercutting kerf cutter, means for operating said second kerf cutter to cut a kerf extending above the under-kerf and substantially at right angles thereto, means for controlling said last-named operating 20 means independently of the operation of said under-cutting kerf cutter, and means for advancing the section carrying said second kerf cutter to a new position along the other section while said under-cutting kerf 25 cutter continues in operation.

31. In a mining machine, the combination with two relatively movable interconnected frames, of an under-cutting kerf cutter on the forward frame, a transverse kerf cutter on the rear frame, means for operating said kerf cutters, means for controlling the operations of said kerf cutters independently of each other, means for controlling the advance of the transverse kerf cutter intermittently to new positions, means on the rear frame for breaking down the material above the under cut and back of the transverse cut, and loading apparatus also mounted on the rear frame and extending to a position adjacent the rear of the transverse cutter.

32. In a mining machine, the combination with two connected but relatively movable frames, of an under cutter on the forward frame, a right angle cutter on the rear frame, means for operating said cutters, means for controlling such operation independently of each other, means for advancing the rear frame relatively to the forward frame to move the right angle cutter to a new position, and means mounted on the rear frame for breaking down the material above the under cut and back of the right angle cut.

33. In a mining machine, the combination with framework comprising two relatively movable interconnected sections, of an under-cutting kerf cutter on the forward section, a transverse kerf cutter on the rear section, means for operating said kerf cutters, means for controlling the transverse cutter independently of the under cutter, means for effecting the advance of the transverse cutter at will to intermittently 65 adjust the same to new cutting positions, a

pick machine mounted on the rear section to break down the material above the under cut and back of the transverse cut, conveying mechanism on the rear section and extending to a position between said pick machine 70 and said transverse kerf cutter, and mechanism for automatically moving the broken down material into position to be acted on by said conveying mechanism, said cutters, pick machine and conveying mechanism being 75 mounted on said framework to constitute a unitary mining and loading machine.

34. In a machine for undercutting, breaking down and loading coal, the combination with framework movable along a path substantially parallel to a coal face, of a low-down laterally projecting horizontal kerf cutter on the framework for undercutting coal to be removed, means for engaging the frame and causing it to move in a fixed path, 80 a blow-striking coal-breaking pick behind said cutter on said framework for breaking down the coal, and means on said framework for removing the broken down coal, said breaking down and removing means 85 performing their respective functions as the said cutter is advanced to form the kerf.

35. In apparatus of the character set forth, the combination of a frame adapted to travel along a coal face, cutter mechanism mounted on said frame and adapted to cut vertical kerfs in the coal transverse to the face thereof, and an impact breaking device mounted on the frame to swing horizontally for the purpose of effectively attacking the body of coal between such kerfs, and to move up and down for the purpose of effectively reaching both the upper and lower parts of the coal.

36. In a mining machine for undercutting, breaking down and loading coal, the combination with supporting framework movable along a path substantially parallel to a coal face, of a low-down laterally projecting horizontal kerf cutter mounted on said framework in position for undercutting the coal to be removed, means for moving said framework in a fixed path, a reciprocable coal-breaking pick on said framework behind said cutter for breaking 110 down the coal, and an endless conveyer mounted on said framework in position for engaging the broken down coal and removing it, said breaking down pick and said conveyer performing their respective functions as the said cutter is advanced to form a kerf.

37. In a mining machine the combination with framework comprising relatively movable sections, of means mounted on one 125 section for cutting a horizontal groove in the material to be mined, means mounted on the other section for cutting a vertical groove in said material, and picking means mounted on said last-named section in posi- 130

tion to act transversely of the vertical groove to break down the material above the horizontal groove and back of the vertical groove.

5 38. In a mining machine, the combination with framework comprising two base sections each adapted to rest on the floor of a mine chamber adjacent an upright mine wall, of means on the forward section for 10 guiding the rear section along the same path of travel as the forward section, cutting mechanism mounted on the forward section, means for driving said cutting mechanism, means for moving said forward section 15 along the mine wall to effect the feeding of said cutting mechanism, dislodging mechanism mounted on the rear section, means for operating said dislodging mechanism while said rear section remains stationary on 20 the floor of the mine chamber and the forward section is moving forward, and mechanism for moving the rear section along the forward section to adjust the said dislodging mechanism to a new position.

25 39. In a mining machine, the combination with a main frame, of a supplemental frame slidably connected thereto, cutting mechanism carried by said main frame, means for operating said cutting mechanism, dislodging mechanism carried by said supplemental frame, means for operating said dislodging mechanism, and rope winding mechanism connected between said frames for effecting the movement of said supplemental frame together with said dislodging mechanism at intervals along said main frame toward said cutting mechanism on said main frame.

40 40. In a mining machine, the combination with a movable frame, of a kerf cutter mounted thereon, means for driving said kerf cutter, means for moving said frame to feed said kerf cutter, a breaking device slidably connected to said frame, means for 45 operating said breaking device during the feed of said kerf cutter, and means for returning said breaking device to its initial position relative to said frame.

45 41. In a mining machine, the combination with a frame, of a kerf cutter mounted thereon, means for driving said kerf cutter, means for moving said frame to feed said kerf cutter, a rod rigidly connected to said frame to extend backwardly therefrom, dislodging mechanism mounted on said rod and 50 slidably along the same relatively to said frame, means for operating said breaking device to break down material adjacent the kerf cut by said kerf cutter, and means for 55 moving the breaking device bodily along said rod relatively to said frame and toward said kerf cutter to restore the breaking device to an initial position relative to said frame.

42. In apparatus of the character set forth, the combination of a frame adapted to travel along a coal face, cutter mechanism mounted on said frame and adapted to cut vertical kerfs in the coal transverse to the face thereof, a reciprocable coal-breaking device mounted on the frame, means for adjusting said breaking device horizontally and vertically for the purpose of attacking the coal between the planes of such vertical kerfs at different heights as 75 may be required, and mechanism for actuating said breaking device.

43. In a coal mining mechanism adapted to travel continuously along the normal front face of a coal bed and to form a relatively shallow horizontal kerf and to remove the coal positioned in the vertical lines by a blow-striking action, the combination of a frame adapted to be moved continuously along said normal front face, a cutter carried by the frame for forming a single relatively shallow horizontal kerf which is continuously lengthened while the machine is in operation, and a blow-striking coal-breaking pick movable bodily on lines parallel to the lines of advance of the kerf cutter and arranged to break down the coal in the vertical lines of said kerf and separated from the overlying material and also separated from its native bed on the innermost vertical lines 95 of the kerf, said pick being adapted to form a transversely advancing face intersecting the planes of the front face by imparting blows in optionally varied directions at points distributed over said transversely 100 advancing face.

44. In a mining machine, the combination with kerf cutting mechanism, of framework for supporting the same, dislodging mechanism mounted on said framework to follow 105 said cutting mechanism at intervals, means for operating said dislodging mechanism during the stopping periods thereof and while said kerf cutting mechanism is moving forward, and means for moving the dislodging mechanism forward at intervals 110 alternating with such stopping periods.

45. In a mining machine, the combination with supporting framework, of a kerf cutter mounted thereon, means for driving said 115 kerf cutter, means for moving a portion of said framework to feed said kerf cutter, dislodging mechanism mounted on another portion of said framework adapted to be held stationary during the feed of said kerf cutter, means for operating said dislodging mechanism during the stopping periods thereof and while said kerf cutter is being fed, and means for restoring the dislodging mechanism to its initial position relative to 120 said kerf cutter at intervals alternating with the stopping periods and after the dislodging mechanism has broken away mate- 125

rial and is free to move toward said kerf cutter.

46. In a mining machine, the combination with kerf cutting mechanism, of a frame for supporting the same, means for driving said kerf cutting mechanism, means for moving said frame to feed said kerf cutting mechanism, a supplemental frame slidably connected to said first-named frame and adapted to follow the latter at intervals, dislodging mechanism mounted on said supplemental frame, means for operating said dislodging mechanism during the continuous forward feed of said kerf cutting mechanism, and means for effecting intermittent forward movement of said supplemental frame together with the dislodging mechanism mounted thereon toward said kerf cutting mechanism for new positions of dislodging operations.

47. In a mining apparatus of the class described, the combination of a frame adapted to be moved while in operation along the normal front face of a native coal bed, means engaging said frame to hold it to predetermined lines of travel along said face, a horizontal kerf cutter carried by said frame, and a blow-striking coal-breaking pick movable bodily on lines parallel to the lines of advance of the kerf cutter and arranged to break down the under cut coal and form a transversely advancing face positioned in vertical planes intersecting the planes of the front coal face and to optionally apply blows in different directions at points distributed over the said transversely advancing face.

48. In a mining apparatus of the class described, the combination of a frame adapted to be moved along and close to the front face of a native coal bed, means engaging said frame to hold it to predetermined lines of travel, a horizontal kerf cutter carried by said frame, a tool holder movable bodily on lines parallel to the lines of advance of the kerf cutter, and a blow-striking coal-breaking pick mounted on said holder and arranged to break down the coal behind the kerf cutter and form a chamber with a transversely advancing wall extending vertically from the horizontal kerf, said pick being adapted to impart blows in optionally varied directions at points distributed over said transversely advancing face.

49. In a mining apparatus of the class described, the combination of a frame adapted to be positioned close, and to be moved parallel to the normal front face of a native coal bed, means to hold the frame to predetermined lines while advancing along the face, an inward projecting horizontal kerf cutter carried by said frame, a tool holder mounted to travel bodily simultaneously with the coal cutter along said front face, a

blow-striking coal-breaking pick mounted on said tool holder and arranged to break down the coal behind said cutter and form a chamber with a transversely advancing wall, said pick being arranged to impart blows to said transversely advancing wall at points distributed vertically and horizontally over its face, and power-actuated feeding means arranged to exert draft on said frame and the pick mounted thereon.

75

50. In a coal mining apparatus adapted to be moved bodily, while operating, on lines close and parallel to the normal front face of a native coal bed, the combination of means for cutting a horizontal kerf in the coal, a conveyer having its forward lower end positioned relatively behind the kerf cutter to receive broken down coal, a power actuated blow-striking coal-breaking pick-like tool positioned to extend for operation to break down the coal adjacent the receiving end of said conveyer, to form a gradually advancing wall with a vertical face in planes intersecting the vertical planes of the normal front face of the coal, said pick being inversely adjustable and adapted to strike blows at points distributed over the face of said transversely advancing wall, means supporting the kerf cutter and the pick, means connecting their supports together, and means for advancing them together bodily along the front face of the coal.

51. In a machine for undercutting, breaking down and loading coal, the combination with framework movable in a path substantially parallel to a coal face, of a low-down laterally projecting horizontal kerf cutter on said framework for undercutting the coal to be removed, means for driving said kerf cutter, means for moving said framework to effect feed of said kerf cutter, a blow-striking coal-breaking pick behind said kerf cutter and adjustably spaced therefrom on said framework, and means for removing the broken down coal, said breaking down and moving means performing their respective functions as the kerf cutter is advanced to form the kerf.

52. In a mining machine, the combination with a supporting frame adapted to have a rectilinear path of travel, of cutting mechanism mounted thereon and movable bodily therewith, said cutting mechanism extending from one side of said supporting frame in position to act on an upright mine wall along a path of travel parallel to the path of travel of said supporting frame, means for driving said cutting mechanism, means for propelling said frame together with said cutting mechanism along such rectilinear paths of travel, an additional supporting frame and connected to said first-named frame for movement relatively thereto and rectilinearly along substantially the same

115

120

125

130

- path of travel as said first-named frame, means for limiting the forward and backward movements of said additional frame along said first-named frame, and restricting the relative movements of said additional frame within predetermined limits relatively to said first-named frame, cutting mechanism mounted on said additional frame and extending from the side thereof above the path of travel of said first-named cutting mechanism, means for driving the cutting mechanism on said additional frame, and mechanism for moving said additional frame together with the cutting mechanism carried thereby forward step by step.
53. In a mining machine, the combination with supporting framework, of an undercutting kerf-cutter mounted on the forward portion of said framework and extending laterally therefrom, an upright kerf-cutter mounted on said framework and extending laterally from said framework to cut a kerf in an upright mine wall above the under-kerf, a pick machine mounted on said framework in a position to act on the cut body of material above the under-kerf and back of the upright kerf from the floor to the roof of the mine chamber to dislodge the cut body of material, and loading apparatus extending diagonally across the said framework toward loading position from a receiving position adjacent the floor of the mine chamber back of the upright kerf-cutter and below the range of action of said pick machine.
54. In a mining and loading machine, the combination with supporting framework, of an under-cutting kerf-cutter mounted thereon, a transverse kerf-cutter mounted on said framework in position to cut an upright kerf above the under-kerf, a pick machine mounted on said framework in position to act on the body of cut material back of the upright kerf and above the under-kerf up to the roof of the mine chamber and to the depth of the transverse kerf, and loading apparatus mounted on said framework and extending toward that side thereof remote from the mine wall from a receiving position adjacent the floor of the mine chamber back of the upright kerf-cutter and below the range of action of the pick machine.
55. In a mining and loading machine, the combination with supporting framework, of a horizontal kerf-cutter mounted thereon, a transverse kerf-cutter in position on said framework to cut an upright kerf extending transversely of the kerf produced by said horizontal kerf-cutter, means for moving said framework along the mine wall to feed said horizontal kerf-cutter while moving said transverse kerf-cutter to a new cutting position, means for driving said horizontal kerf-cutter during the feed thereof, means for feeding said transverse kerf-cutter during a stopping period of said framework, means for driving said transverse kerf-cutter during such feed thereof, means for controlling the starting and stopping of said framework, means mounted on said framework in position to act on the cut body of material above the under-kerf and back of the transverse kerf to dislodge such cut material, and loading apparatus mounted on said framework and extending toward loading position from a receiving position back of the transverse kerf and below the range of action of said dislodging means.
56. In a mining and loading machine, the combination with supporting framework, of a single horizontal kerf-cutter mounted on said framework, means for driving said kerf-cutter, propelling mechanism for said framework to secure feed of said horizontal kerf-cutter, a single upright transverse kerf-cutter, means for operating said transverse kerf-cutter relatively to said framework to cut an upright kerf above the under-kerf, a pick machine mounted on said framework in position to act on the cut body of material to dislodge the same above the under-kerf and back of the upright kerf, and loading apparatus mounted on said framework in position to extend toward loading position from a receiving position adjacent the floor of the mine chamber back of the upright kerf and approximately below the range of action of said pick machine.
57. In a mining and loading machine, the combination with supporting framework, of an undercutting kerf-cutter mounted on said framework, an upright transverse kerf-cutter mounted on said framework, means for operating said kerf-cutters to cut a body of material remaining integral with the unmined mass at its upper and rear ends, a pick machine mounted on said framework in position to dislodge such cut body of material from said unmined mass up to the roof of the mine chamber and back to the depth of the upright kerf, and loading apparatus mounted on said framework in position to automatically receive the dislodged material and convey it toward loading position.
58. In a mining and loading machine, the combination with supporting framework, of an undercutting kerf-cutter extending laterally from said framework in position to cut a kerf approximately in the plane of the floor of the mine chamber, an upright transverse kerf-cutter mounted on said framework in position to cut a kerf above the under-kerf, means for operating said kerf-cutters to cause the first-kerf-cutter to cut a kerf in advance of the transverse kerfs, and to cause the transverse kerfs to be cut at intervals in spaced-apart positions along the mine wall, a pick machine mounted on said framework

in position to dislodge the material above the under-kerf and back of the upright transverse kerf up to the roof of the mine chamber and to the depth of said upright kerf, endless 5 flight conveyer mechanism mounted on said framework in a position to extend toward an elevated loading position from a receiving position adjacent the floor of the mine chamber, and a device mounted on said 10 framework in position to move over the smooth floor formed by said under-kerf-cutter and move the dislodged material into the receiving end of said endless conveyer mechanism from the place where it falls upon being 15 dislodged by said pick machine.

59. In a coal mining machine, the combination with supporting framework comprising two sections relatively movable but confined to predetermined relative limiting 20 positions, of a cutting tool mounted on one of said sections and movable bodily therewith, dislodging mechanism mounted on the other section and movable bodily therewith, means for operating said cutting tool including 25 the continuous forward feed thereof, and means for controlling the forward movements of the said other section relatively to the forward section to secure stopping periods at intervals for operation of said 30 dislodging mechanism.

60. In a coal mining machine, the combination with supporting framework, comprising two sections having limited relative movement but permanently connected together in fixed relation with the relative limiting positions predetermined, of kerf-cutting mechanism mounted on the forward section and movable bodily therewith, means for operating said kerf-cutting mechanism 40 including feed thereof by continuous forward movement of said forward section, dislodging mechanism on the rear section, means for moving the rear section forward relatively to the forward section, said rear section having stopping periods at intervals while said forward section continues its forward movement, and means for operating the dislodging mechanism during the stopping periods.

61. In a mining machine, the combination with supporting framework, of a cutter mounted on said framework in position to under-cut a body of coal, a second cutter mounted on said framework in position to 55 cut such body of coal transversely of the plane of the undercut and transversely of the face of the mine wall, said second cutter being initially out of engagement with the coal, means for operating said cutters including the feed of each, and means for moving the said framework along the mine wall to effect the feed of the under-cutter and to move the transverse cutter to new positions at intervals along the mine wall.

62. A machine for under-cutting, breaking-down and loading coal, the combination with framework movable along a path substantially parallel to a coal face, of a laterally projecting horizontal kerf-cutter on the framework to cut an under-kerf the bottom 70 of which is approximately in the plane of the floor of the mine chamber, means for moving said framework along a predetermined path, a pick machine behind said cutter on said framework acting by percussive blows to 75 break down the coal at the mine wall above said under-kerf, and loading apparatus extending toward an elevated loading position from a receiving position on said framework adjacent the plane of the under-kerf back 80 of the under-cutting kerf-cutter and below the range of action of said breaking-down means.

63. In a mining mechanism adapted to travel continuously along the normal front 85 face of a coal bed and to form a relatively shallow horizontal kerf which extends on longitudinal lines inward from the front face and on transverse lines along said face and to also form a chamber which widens 90 vertically from the horizontal kerf and is gradually elongated transversely along the face and has at its forward end a transversely advancing vertical wall in planes intersecting the walls of the normal front 95 face of the coal, the combination of a frame movable continuously along said normal front face, an inward projecting horizontal kerf cutter carried by the frame, a tool holder carried by said frame, a blow-striking coal-breaking pick mounted on said holder and adjustable as set forth to impart 100 blows to the coal at optionally selected points distributed vertically and longitudinally over the said transversely advancing 105 longitudinal face.

64. In a mining mechanism adapted to travel continuously along the front face of a coal bed and form a single relatively shallow horizontal kerf and to dislodge the coal 110 remaining in the vertical lines of said kerf and form parallel to the face a gradually elongating transverse chamber by intermitting coal dislodging blows which separate the undercut coal by cleavage from the 115 overlying material and by cleavage separate it from the solid mass beyond it, the combination of a frame, means for moving it along said normal front face, a cutting mechanism carried by the frame which forms a 120 single relatively shallow horizontal kerf, a blow-striking coal-breaking pick arranged to impart blows to the coal and form behind the kerf cutter a chamber with a gradually advancing forward wall and to break the 125 coal above the kerf from the solid material above it and also break it from the solid native coal behind it, said coal breaking pick

being connected to the frame and to the kerf cutter, to be moved therewith along the face of the coal.

65. The combination in a coal cutting and breaking-down machine, of a main frame adapted to be moved parallel with a coal face, a kerf cutter mounted on said frame for cutting kerfs in the coal at an angle to the front face thereof in different places along the face of the coal according to the position of the machine, a reciprocable breaking down device mounted on said main frame and adjustable and operable independent of the kerf cutter, a bearing adjustable on said frame and having means for guiding the sliding of said breaking-down device, mechanism for actuating the latter, and a conveyer on the frame for engaging and removing the broken-down coal.

66. The combination in a coal cutting and breaking-down machine, of a main frame adapted to be moved parallel with a coal face, a kerf cutter mounted on said frame for cutting kerfs in the coal at an angle to the front face thereof in different places along the face of the coal according to the position of the machine, a reciprocable breaking down device mounted on said main frame and adjustable and operable independent of the kerf cutter, a bearing for supporting and guiding the breaking-down device, said bearing being adjustable on said frame to shift the axis of the breaking-down device in vertical and in horizontal planes, and mechanism for actuating the breaking-down device.

67. The combination in a coal cutting and breaking-down machine, of a main frame adapted to be moved parallel with a coal face, a kerf cutter mounted on said frame for cutting a kerf in the coal at an angle to the front face thereof, a reciprocable breaking-down device mounted on said main frame above said kerf cutter and adjustable and operable independent of the kerf cutter, a bearing adjustable on said frame and having means for guiding the sliding of said breaking-down device, mechanism for actuating the latter, and a conveyer on the frame for engaging and removing the broken-down coal.

68. The combination in a coal cutting and breaking down machine, of a main frame adapted to be moved parallel with a coal face, a kerf cutter mounted on said frame for cutting kerfs in the coal at an angle to the direction of movement of said frame in different places along the face of the coal according to the position of the machine, a reciprocable breaking down device mounted on a universal pivotal support, and a support for said pivotal support on said main frame and adjustable relative to said kerf cutter.

69. In apparatus of the character set

forth, the combination of a frame adapted to travel along the coal face, cutter mechanism mounted on said frame and adapted to cut vertical kerfs in the coal transverse to the face thereof, and a reciprocable coal-breaking device inversely mounted on said frame for adjustment horizontally and vertically for the purpose of attacking the body of coal between the planes of the vertical kerfs cut and also attacking the coal between such planes at various heights as may be required.

70. In a mining and loading machine, the combination with a frame, of core-cutting mechanism connected thereto, means for operating said core-cutting mechanism including feeding movement thereof, a conveyer connected to said frame in position to receive dislodged material and capable of operating in initial position at the floor of the mine chamber, and means for moving the conveyer along the feeding path of travel of said core-cutting mechanism.

71. The combination of a main frame movable along a coal face, a horizontally projecting cutter to undercut the coal, a receiving plate occupying a position in the plane of the kerf beneath the undercut coal, a conveyer extending from said receiving plate away from the coal face and mounted on said frame to follow the lines of travel of said undercutter, motor and power mechanism on said frame in advance of said conveyer, and means for breaking down the coal adapted to attack the coal above the conveyer and on vertical planes at an angle to the front face of the coal.

72. The combination of a main frame movable laterally along a coal face, cutting apparatus projecting from said frame in position to undercut the coal, means on said frame outside the bounding lines of the coal face for moving the frame and cutting apparatus along the face of the coal, and a coal-breaking pick carried by said frame and arranged to impart blows on the coal on upright planes approximately at right angles to the front face of the coal.

73. The combination of a main frame movable laterally along a coal face, cutting apparatus projecting from said frame and comprising means to undercut the coal, means on the frame outside the boundary lines of the coal face for moving the frame and the undercutting means along the face of the coal, an extension from said frame to a receiving position in the plane of the undercut, an endless conveyer mounted on said frame and movable bodily therewith, means for operating said conveyer to transfer dislodged material from said receiving extension toward loading position, and a coal-breaking pick carried by said frame and adapted to form a free face on the coal inside of and at an angle to its normal front

face and said pick being arranged to impart blows to such a free face while bodily advancing with the cutting apparatus.

74. In a machine of the character described, the combination with a frame, of means movable relatively thereto for cutting a horizontal kerf in the material to be mined, means for cutting a vertical kerf, and picking means operating from the machine and acting transversely to the vertical kerf for breaking down the material.

75. In a mining machine, the combination with a traveling base member, of a horizontal rotary cutter, a vertical rotary cutter, and picking means acting transversely to said vertical cutter for breaking down the material.

76. A mining and loading machine comprising a supporting frame, kerf-cutting mechanism mounted thereon, means independent of the movement of said frame for dislodging the material adjacent the kerfs produced by said kerf-cutting mechanism, and mechanism mounted on said frame for automatically sliding the dislodged material over the floor of the mine toward loading position.

77. In a mining and loading machine, the combination with mechanism for dislodging material from a mine wall comprising means for producing an under kerf, of a frame for supporting said dislodging mechanism, loading apparatus connected to said frame, and a device mounted on said frame in spaced apart relation to said dislodging mechanism in position to extend from said frame toward the mine wall to operate in the plane of the under kerf for moving dislodged material onto said loading apparatus from the position assumed by said material after being dislodged.

78. In a mining and loading machine, the combination with supporting framework, of mechanism mounted thereon for producing kerfs in intersecting planes in a mine wall, means mounted on said framework and extending rearwardly therefrom for breaking down the material bounded by said kerfs, and apparatus comprising an endless traveling conveyer for automatically taking the dislodged material from the floor of the mine chamber and transferring it toward loading position.

79. A mining and loading machine comprising a supporting frame, of mechanism mounted thereon for producing kerfs in intersecting planes in a mine wall, means for dislodging material bound by said kerfs, a conveyer mounted on said frame and extending to a receiving position near the floor of the mine chamber, and automatic means for taking the dislodged material from the floor of the mine chamber and moving it onto said conveyer.

80. A mining and loading machine com-

prising a supporting frame, kerf-cutting mechanism mounted thereon, a pick machine mounted on said frame for breaking the cut material to dislodge the same onto the floor of a mine chamber adjacent said frame, a conveyer mounted on said frame, and means mounted on said frame for mechanically transferring onto said conveyer the said material on the floor.

81. A mining and loading machine comprising a supporting frame, kerf-cutting mechanism mounted thereon, means mounted on said frame near said kerf-cutting mechanism for dislodging the material adjacent the kerfs produced by said kerf-cutting mechanism, a conveyer mounted on said frame and extending to a receiving position near the floor of the mine chamber and adjacent said frame, and means on said frame for automatically transferring the dislodged material from the floor onto said conveyer.

82. A mining and loading machine comprising a supporting frame, kerf-cutting mechanism thereon, a pick machine mounted on said frame near said kerf-cutting mechanism to break down the cut material onto the floor adjacent said frame, and loading apparatus mounted on said frame for taking the broken down material off the floor and moving it toward loading position.

83. A mining and loading machine comprising a supporting frame, kerf-cutting mechanism mounted thereon, means independent of the movement of said frame for dislodging the material adjacent the kerfs produced by said kerf-cutting mechanism, and mechanism mounted on said frame for automatically sliding the dislodged material over the floor of the mine along the mine wall toward loading position.

84. A mining and loading machine comprising a supporting frame, kerf-cutting mechanism mounted thereon, mechanism mounted on said frame near said kerf-cutting mechanism to dislodge the cut material onto the floor of the mine chamber adjacent said frame, a conveyer on said frame extending to a receiving position substantially at the floor of the mine chamber, and means mounted on said frame for sweeping the dislodged material from the floor onto said conveyer.

85. A mining and loading machine comprising a frame, kerf-cutting mechanism mounted on said frame, means for moving said frame and said cutting mechanism bodily to effect feeding of said cutting mechanism, means for actuating said cutting mechanism during the forward feed of the latter, breaking mechanism connected to said frame and movable bodily therewith during the forward feed thereof to act on the material extending back from said cutting mechanism, mechanism for effecting intermittent operation of said breaking mechanism auto-

matically during the forward feed of said cutting mechanism, and conveyer mechanism connected to said frame and movable therewith and extending to a position to receive 5 the dislodged material and convey it toward loading position.

In testimony whereof I have signed my

name to this specification, in the presence of two subscribing witnesses, on this 21st day of June A. D. 1910.

EDMUND C. MORGAN.
